UNITED STATES PATENT OFFICE

TERRENCE G. LOUIS, OF WEST SPRINGFIELD, MASSACHUSETTS, ASSIGNOR TO WICO ELECTRIC COMPANY, OF WEST SPRINGFIELD, MASSACHUSETTS, A CORPORATION OF MASSACHUSETTS

MAGNETO

Application filed November 19, 1930. Serial No. 496,750.

This invention relates to an improved magneto of the type having an unwound inductor or armature, rotatable continuously in one direction, as distinguished from the type having a partially rotatable inductor which oscillates back and forth. The invention makes use of certain of the important teachings of the Ira E. Hendrickson Patent No. 1,736,441, dated November 19, 1929, but these are utilized in a somewhat different way, resulting in a markedly different magneto, having important advantages. In common with the Hendrickson invention, the present invention makes use of an unwound inductor cooperating with two cores or pole pieces of a magnetic circuit to produce intermittently a double break in said circuit and at all other times to maintain said circuit closed except for the small double air gap between the inductor and cores, representing the running clearance between these elements. Unlike the Hendrickson patent, the notches in, or non-magnetic portions of the inductor are diametrically opposed and the inductor rotates between the inner ends of the cores, the axes of which are in alignment and also coincide with one diameter of the inductor. The magnetic source, such as a bank of permanent magnets, is disposed parallel to said axes and diameter and is spaced therefrom substantially just sufficiently to clear the inductor,—the innermost face of the magnetic source lying almost tangential at its neutral point to the inductor. Primary and secondary coils and breaker point mechanism, controlling the primary coils, are used as in the Hendrickson patent but the coils, being disposed one on each of said cores, are axially aligned and their end faces are disposed in planes at right angles to the magnets and with their inner end faces nearly tangential to the periphery of the inductor. The cores have extensions for connection to the polar extremities of the magnetic source and the outer face of each such extension lies within a circle struck from the axis of the inductor as a center, and with a radius equal to the distance from said axis to the outer end of a core. No parts of the magnetic circuit and no parts of the coils project outside said circle. Like the Hendrickson patent, the spark is produced on the breaking of the magnetic circuit rather than on the making thereof and, preferably also, the building up of flux in the magnetic circuit is allowed to occur, at least in part, under the favorable condition of an open circuited primary winding. Such winding is maintained closed except at the intermittent intervals necessary to produce the spark and enable the ensuing initiation of the building up of flux in the magnetic circuit. The problem of this invention is to produce an exceedingly small, light weight, and compact yet highly efficient magneto, capable of being housed within a very small flywheel, such for example as that of an outboard motor, or in the small free central space available in a flywheel, which also serves as a fan and in which a substantial amount of annular space is utilized for the reception of fan blades. A flywheel of the last named type is shown in the Hendrickson patent and, as will be clear from the drawings of that patent, the Hendrickson magneto is incapable of being housed within the small confines of such a flywheel. What has been done in the present invention is to redesign the various parts of the magneto and mount them around the inductor to fit within the small space available. The magnets of the Hendrickson magneto have been pulled in to lie as close as possible to the periphery of the inductor, the cores and coils have been relocated to lie in diametrically opposed relation on opposite sides of the inductor and also materially shortened, but the shortening of the coils has been effected without materially increasing their diameter. The core extensions have been curved to lie concentric with the axis of the rotor or otherwise so formed as not to extend beyond a circle struck with what may be termed the limiting radius, which is the radial distance from the axis of the rotor to the outer end of a core. This radial distance has been reduced to a minimum and all other parts have been made to lie within the confines of a circle struck with said

55

60

limiting radius from the axis of the inductor as a center. All this has been effected without any reduction in length of the magnets. The same desirable long magnets of the Hendrickson magneto can be used and yet their extremities have been made to lie at a much smaller radial distance from the axis of the inductor.

The magneto of this invention is a unitary structure, complete in itself. It can be added on to any engine without necessitating special design of engine parts, as distinguished from the many prior art magnetos which require that the magneto be "built into" the engine. The magneto manufacturer furnishes the complete unit, even to a casing which cooperates with the flywheel of the engine to fully enclose all working parts, and all that the engine manufacturer has to do is to fasten this unit in place.

The present invention represents the results of the utilization of a minimum amount of material in the most efficient and effective way to produce a commercially successful magneto in which the parts have been compressed and compacted into such small compass that the entire unit will fit within the confines of the smallest flywheels of small engines.

There are many other features contributing to the accomplishment of the general objects above set forth and these and other objects of the invention will appear as the detailed description proceeds and be particularly pointed out in the appended claims.

The invention will be disclosed with reference to the accompanying drawings, in which:—

40 Fig. 1 is a front elevational view of a magneto embodying the invention;

Fig. 2 is a sectional view taken on the line 2—2 of Fig. 1;

45 Figs. 3 and 4 are views showing the application of the magneto to a fan type flywheel,—Fig. 4 showing the flywheel and magneto casing in section and the magneto in end elevation while Fig. 3 shows the magneto in rear elevation and its casing in section;

50 Figs. 5 and 6 are end and front elevational views, respectively, of one of the stationary laminated field elements and coil units;

55 Fig. 7 is a front elevational view of the magneto frame;

Fig. 8 is a fragmentary cross sectional view illustrative of one mounting of the magneto frame on an engine;

60 Fig. 9 is a similar view illustrative of one form of driving means for the magneto;

Fig. 10 is an enlarged, fragmentary, front elevational view of the breaker point cam;

65 Fig. 11 is an elevational view of an out-

board motor showing the application of the magneto thereto;

Fig. 12 is a plan view of the flywheel showing the rotor of the magneto mounted thereon; and

Figs. 13 and 14 are sectional views illustrative of the mounting of the movable and fixed elements, respectively, on the movable and fixed elements of the motor.

Referring to these drawings; the magneto includes a source of magnetic flux,—such as the permanent magnet 20 (Figs. 1 and 2),—laminated extensions 21 (Fig. 1), connected one to each polar extremity of the magnet and terminating with integrally connected but inturned cores 22 (see also Figs. 5 and 6), on each of which is placed a coil element or unit, comprising a primary and a secondary winding 23 and 24 (Fig. 6), respectively. Cooperating with the inner ends of the inturned cores 22 is a rotary inductor 25 (Fig. 1), which is built up of laminations in the form of a hollow cylindrical member, except for substantially diametrically opposed notches 26, or equivalent non-magnetic portions, in its outer periphery. The inductor, except for said portions, presents a smooth cylindrical surface running in close proximity to the concentrically curved inner ends of the cores 22. The magnetic circuit from the magnet through the extensions, cores and inductor is normally closed, except for the small double air gap between the inductor and cores, necessary for clearance between these elements. When, however, the two notches 26 register with the two cores, a double break in the magnetic circuit is effected.

For efficiency and to secure satisfactory results, these notches 26 need to be slightly greater in peripheral extent than the width of the core but their peripheral extent should not be greatly in excess of such width. The notches should be just long enough to afford an air gap between each radial wall of the notch and the adjacent edge (upper or lower as the case may be) of the core, which air gap is of an extent sufficient to secure an effective break in the magnetic circuit. Such gaps are measured when the radial center line of a notch coincides with the axis of the core. Each such air gap should be of about the same extent as, and at least no greater than, the radial gap between the curved inner end of a core and the bottom wall of the notch. Any excess length in the notches detracts from the efficiency of the machine, other factors being the same, and it is important to have as much peripheral extent as possible of smooth unbroken cylindrical surface of the rotor not only in order to hold the flux in the magnetic circuit but to allow time for flux to build up in such circuit against a

short circuited primary circuit, as will later appear.

The primary coils are suitably connected in a closed electrical circuit, which is controlled by relatively fixed and movable breaker points 27 and 28 (Fig. 1). These coils may, for example, be connected as shown in series by a wire 29. One terminal of one coil is connected by a wire 30 to an insulated terminal 31 and thence by a metal bracket 31', bolt 31² and spring 32 to the metallic part 33 of a breaker point lever, which part carries the breaker point 28. This lever is pivoted at 34 and is suitably mounted in and insulated from a metallic housing 35, secured to a non-magnetic plate 36 fixed, as will appear, to the stationary field structure. The breaker point lever also has a part 37 of insulating material for engagement by a cam 38, carried by the rotary inductor. The fixed breaker point 27 is supported in housing 35 and in metallic connection therewith and with the field structure of the magneto. A condenser 39 has one terminal connected to the insulated terminal 31 and the other "grounded" to the field structure. The primary circuit is completed by "grounding" the other primary coil to the field structure, as by the wire 39'. 20 The secondary coils, forming the generating winding, may be connected in any suitable way. They are usually connected in series, as by a wire 40, and one of them is grounded as by a strap 41 secured to the field structure,—leaving a terminal 42 for connection in any suitable way to the ignition system of the engine,—in this case directly to a spark plug such as 43 (Fig. 11) by means of a wire 44.

40 From the foregoing description it will be clear that the magnetic circuit is maintained substantially closed by the inductor during the major part of its revolution. Also, that the primary circuit is likewise maintained closed by the breaker points 27 and 28, which are pressed into contact by spring 32, except when momentarily separated by cam 38. Assuming that flux has been built up in the magnetic circuit and that the rotor, turning in the direction of the arrow, has come into the position shown in Fig. 1, the notches 26 in the inductor register one with each core 22 and the magnetic circuit through the coils is broken. The cam 38 is about to move the breaker point lever and separate the breaker points. At substantially the same time that the double break occurs in the magnetic circuit, the primary circuit is opened, and a very rapid decrease in flux through the coils results, causing the generation of an E. M. F. in the secondary coils and the production of a spark at plug 43. It will be noted that the flux change utilized for the production of the spark is 65 that which occurs on the breaking rather

than the making of the magnetic circuit. This is of great importance because a more rapid and thus more effective change of flux is secured on the breaking than can be secured on the making of the magnetic circuit. 70

Referring next to the operation of building up flux in the magnetic circuit in readiness for the production of another spark, this operation is preferably initiated under the most favorable condition, which is that of an open circuited primary winding. It will be noted that cam 38 is constructed with a dwell to hold the breaker points separated during an appreciable interval. As shown, this interval is long enough to allow the edge of the "trailing" radial wall of each notch to reach substantially to the center of the adjacent core at which time the breaker points will close. The primary circuit is thus held open long enough to reestablish the magnetic circuit by the inductor. Consequently, a building up of a substantial amount of flux occurs under the most favorable condition of an open circuited primary winding. Such winding then exercises no restraining influence to oppose the building up of flux and a rapid increase of flux occurs in a very short time. I believe that a large part of the flux is built up at such time. While full coverage of the cores by the inductor is not secured prior to the closing of the breaker points, there is enough coverage to permit a substantial part of the flux to be built up and enough so that the remainder can be completed, even though at a slower rate, against the opposing influence of the closed circuited primary winding. The long dwell between the notches of the inductor is important to allow continued building up of flux after the breaker points close and also, of course, for the purpose of retaining the flux already built up. 95

As shown, there are two positions of the rotor, in each revolution thereof, where the magnetic circuit is broken and only one of these is utilized in the illustrated magneto. Obviously, by providing for a second opening of the breaker points when the second break in the magnetic circuit occurs, the second break can be utilized. In the present case, this second break in the magnetic circuit will undoubtedly result in some loss of flux although the loss is minimized by keeping the primary winding closed at the time so as to restrain a decrease of flux. But, after the second break, there is time to permit rebuilding of flux to compensate for the aforesaid loss. The disadvantage due to loss of flux, in using two notches, is more than offset by the advantages resulting from the double break effected by these notches. 100 115 120 125

The foregoing description will illustrate the type of magneto that is desired and the preferred manner of operation thereof for securing effective and commercially satisfac- 130

tory results. The conditions stated are important and most desirable. Nevertheless the magneto can be operated in other than the exact way described and the mode of operation as above set forth, is to be taken as illustrative of what I now believe to be the best mode of operation.

The present invention seeks to utilize all the desirable features and conditions of magneto operation, as above set forth, and yet to mount the stationary magneto parts as closely as possible around the rotor so that the resulting structure will be compact enough to be placed within a very small flywheel. The present invention is in sharp contrast to that of the aforesaid patent in the sense that the magneto parts have been compacted into small enough compass to fit within the inner annular space of the flywheel shown in said patent, whereas the magneto of the patent clearly will not fit into said space. And yet, the resulting magneto is sufficiently effective to satisfy the exacting demands of the trade.

What has been done is to pull in the magnet 20, locating it so that at its neutral point it lies closely adjacent and nearly tangential to the periphery of the rotor (Figs. 1 and 2). The magnet is no shorter than that of said patent. The inductor itself is made as small as possible but little reduction can be effected here because of the fixed factor of a large central opening for the engine crank-shaft. Also, there is a definite minimum cross sectional area of iron required for conducting the desired amount of flux. The minimum cross sectional area is at the notches and, as shown, is half that at unnotched portions of the inductor. Since the flux, in flowing from one core to another, divides into two streams on opposite sides of the rotor axis, these two portions of least area do not restrict the flow for each takes only half the flux. With the outside diameter of the rotor fixed to a minimum compatible with the conditions imposed, cores, of a length as short as possible, compatible with coil requirements, are mounted one on each side of the rotor. These cores extend radially from the inductor and preferably in diametrically opposed relation, or substantially so. The coils are made as short as possible. As shown, the coil element as a whole, is of a diameter twice its length. The diameter of the coil is made as large as possible so that its length may be made as short as possible. These, the preferred proportions of the coil element, are most desirable and important as enabling the compact arrangement. The coil elements are made to substantially fill the space between the cores and the magnet or, more properly, the surface 46 of the polar extension 21. By this arrangement the length of the core, measured from its curved inner face to its junc-

tion with the inner face 47 of its polar extension 21 is substantially less than the radius of the inductor. The extension 21, at its lower end, must have a definite minimum cross sectional area for flux conducting purposes and this means an addition to the outer end of the core. The aforesaid conditions fix the minimum radial limits of the magneto. The radial distance from the axis of the inductor measured along an axis of the core to the outer curved face 48 of an extension 21 has been reduced to a minimum for the desired magnetic and electrical characteristics of the machine. Such distance is what I term the "limiting radius". With this radius as a limiting dimension, I have made all other parts of the magneto proper, such as the magnets and polar extensions, lie within the limits of a circle struck with said radius from the axis of the inductor as a center. As shown, the surfaces 48 are curved concentrically with the axis of the inductor but they may be otherwise formed and still lie within the limits specified. The magnets, although of the simple, straight-bar form desirable for manufacturing economy, are of the usual length and yet by moving them in as closely as feasible to the periphery of the inductor, their ends lie wholly within said circle.

Referring now to the details of the magneto, the permanent magnet 20 is a composite one, composed of a central stack of superposed straight bar magnets of rectangular cross section (Fig. 2) and of equal dimensions and other like magnets placed on edge, one on each side of the central stack. The width of the outer magnets, thus placed on edge, is substantially equal to the combined thicknesses of the magnets which compose the central stack. This assembly of magnets is suitably held (as by endwise pressure) between the upper ends of the two laminated iron extensions 21 each of which is preferably recessed as shown, to receive and closely fit the assembly of magnets. The laminated extensions 21 are suitably bound together as by rivets 49 and by bolts 50 and 51,—these bolts serving also to bind the entire stationary field structure to a supporting frame, herein shown as a flat non-magnetic metal plate 52, suitably recessed to enable the engine crankshaft to pass centrally therethrough.

It is to be noted that the cores 22 have to be supported far enough forwardly of plate 52 to provide clearance space for the coil elements; also, that the composite permanent magnet is wider than the cores. Because of the latter condition, additional laminations 21' are provided to widen out the extensions 21 to the width of the magnet. These additional laminations are, for the most part, placed between the core laminations and plate 52 in order to fill up the

70

75

80

85

90

95

100

105

110

115

120

125

130

clearance space. The core laminations have integral parts forming the extensions. The laminations 21' are cut to the shape of the extensions except that they terminate with rounded lower ends through which the bolt 51 passes. A few laminations, similar to those marked 21', are placed in front of the core laminations to form a shoulder for the coil element.

- 10 Each coil element comprises a hollow cylindrical casing 53 of insulating material closed at one end and having inner and outer circular walls projecting from the end wall in concentrical relation; forming an annular space into which the secondary coil 24 is placed. Usually sealing compound 54 (Fig. 6) is poured into this space to seal the coil in its casing and a split sealing ring 54' is applied to close the outer end of the 15 annular part of said casing. The primary coil is pressed into the space within the inner circular wall. The casing 53, with the coils assembled therein, is slid onto a core 22 until its closed end abuts the shoulders 20 formed by the laminations 21 and 21'. The flat face 47 of these laminations affords a 25 substantial area for such engagement by the casing 53.

It is important to hold these casings 53 30 in place on their cores, not only to prevent breakage of the electrical connections but also to prevent axial displacement of the coils on the cores such as might cause the coils to rub on the revolving rotor 25 and 35 be damaged thereby. To this end, I may provide on each core a flat strip 55 (Fig. 6) of metal, secured thereto by one of the rivets 49. After the casing 53 has been put in place, the end of this strip is bent over the 40 inner and open end face of the casing (Fig. 5) to hold it in place on the core with its closed end pressed tightly against the surface 47. As an alternative or as additional security, I provide for the purpose, outwardly turned ears 55' on a plate 56, secured 45 by cap screws 56' to plate 52 (Figs. 1 and 7). These ears are so located that each will engage an inner face of a casing 53 and force it against its locating shoulders. These securing means not only prevent axial displacement of the coils but also, by frictional engagement therewith tend to prevent the coils from turning on the cores. Additional security against turning of the coils may 50 be had by wedges 57 (Figs. 5 and 6) placed between the cores and the primary coils 23.

It will be seen that the stationary elements of the magneto are bound together into one unit and held to the support 52 55 by the bolts 50 and 51. The heads of these bolts are preferably countersunk (Fig. 2) into the support 52 so as to lie flush with its back face and the bolts extend through the support, spacing washers 58, and the laminations 21' and 21,—also in the case of the

upper bolts 50, through the non-magnetic cross bar 36. The left hand bolt 50 also serves to clamp the ground connections for the condenser 39 and the breaker point housing to the field structure and to fasten there-to the ground strap 41 of the secondary winding. A desirable plan of fastening the field structure to plate 52 is one which enables limited pivotal movement of the connected elements 21, 21' and 22 about the bolt 50 as an axis. For example, the hole through which bolt 51 passes, may be made larger than the bolt to permit this action, as shown in Fig. 6. In this way, the inner ends of cores 22 may be moved toward or away from the periphery of the inductor to adjust the clearance therebetween.

The rotary inductor may be mounted in various ways. The simplest way is to fix it directly to the crankshaft or flywheel (Fig. 12). If this plan be followed, there will be no magneto parts requiring lubrication. The disadvantage of this plan is that the magneto rotor will partake of any unevenness in the running of the crankshaft or flywheel, such as wobbling or eccentricity. For maximum efficiency, a close running fit between the rotor and cores is needed and it is difficult to maintain this close fit unless the crankshaft runs true, which it often does not. A preferred plan which guards against the possibility of uneven running crankshafts and places the sole responsibility for the proper running fit between the rotor and cores squarely upon the magneto manufacturer, where it belongs, is to provide the magneto with a bearing for the rotor. For example, a hollow stud 60 may be provided on plate 52 to receive and rotatably support a bearing sleeve 61 fixed to the rotor 25. This stud projects forwardly from the front face of plate 52 and encompasses the crankshaft 8 with sufficient clearance therebetween to take care of any unevenness in the running of the crankshaft. The rotor may then be driven in any suitable way from the crankshaft or flywheel so as to prevent the wobbling or eccentric movements of the latter from being communicated to the rotor. For example, a drive pin 63 (Figs. 4 and 9) supported eccentrically from the flywheel 7 may project forwardly toward the rotor with its free end received in an opening therein. This drive pin is desirably somewhat flexible (that shown is of music wire) and it may also be flexibly supported as by the split collar 64 in which it is supported for limited rocking movement. A spring 65 on the drive pin may be used as a means for retaining the inductor 25 in proper axial position on its bearing stud 60. As shown herein, the stud 60 has a flange 66 at one end which is secured with plate 56 by cap screws 56' to plate 52.

Where the inductor is fixed to the fly-

wheel, it is desirable to do so in the manner shown in Figs. 12 and 13. The inductor is pressed onto a sleeve 67 which encompasses the hub *h* of the flywheel *f'* and has a freely sliding fit therewith. This sleeve has a flange 68 which is secured by screws 69 to the flywheel. The inductor, after having been pressed onto the sleeve with a drive fit, is afterwards machined so that its periphery is true and concentric with the sleeve. If the inductor were pressed onto the hub *h* by the engine manufacturer and not thereafter machined, there is a danger that its periphery might not be true because of possible distortions resulting from the driving of it onto the hub. The suggested plan enables the magneto manufacturer to furnish to the engine manufacturer a properly machined inductor with a convenient attaching means therefor and one which can be applied with assurance that the periphery of the inductor will not be distorted by the engine manufacturer in the act of fastening the inductor in place.

The stationary magneto elements, carried by plate 52 may be mounted on the engine in any suitable way. In many cases, these elements need to be movable within the limits, about the axis of the inductor, to vary the timing of the spark. In other cases, they may be rigidly fixed. In most cases also, it is desirable that the magneto be enclosed to protect the parts and I provide a casing 71 of thin pressed metal for this purpose. This casing is substantially cup shaped in form, having an end wall 72, perforated centrally to encompass the crankshaft *s* and a circular flange 73. The latter cooperates with some circular part of the flywheel, as shown in Fig. 4, to afford an enclosure for the magneto parts. Where enclosure of the parts is not desired, the casing may be omitted. When the casing is used, the inner face of its end wall 72 lies flat against the back wall of plate 52 (Fig. 4) and these two elements are secured to any suitable part of the engine, such as the hub *h'* of the crankcase, by cap screws 74 (Fig. 8). This hub preferably has a machined cylindrical surface 75 to closely fit in the central hole 76 (Fig. 3) of plate 52 as a pilot,—thereby locating the stationary magneto elements in proper relation with the axis of the crankshaft. This locating feature is obviously not so important where the magneto is provided with a bearing of its own for the rotary inductor.

Where it is desirable to shift the relatively stationary elements of the magneto about the axis of the inductor for timing purposes, I provide the mounting shown generally in Fig. 11 and in detail in Fig. 14. In Fig. 11, there is shown a two cylinder outboard motor of a well known type,—the cylinders being marked *c*, the crankcase *c'*,

the gasoline tank *t* and the flywheel *f'*. The crankshaft *s* passes out of crankcase *c'* through a hub *g*. The inductor is mounted on the inner face of flywheel *f'* as above described, and as shown in Figs. 12 and 13. The relatively stationary elements of the magneto are the same as shown in Fig. 1 and they are contained within the casing 71 and bolted to the frame plate 52. The pilot hole 76 of plate 52 is received on the periphery of a split sleeve 77, having at one end a circular flange 78. The plate 52, end wall 72 of casing 71, and a plate 79 interposed between wall 72 and flange 78, are clamped to said flange by bolts 80. The sleeve 77 is turnably mounted on a cylindrical part 81 of hub *g* and its end flange 78 seats against a shoulder 82 on this hub. A split clamping strap 83 encompasses the other end of the split sleeve 77 and serves to hold the latter frictionally to the hub,—a bolt 84 serving to draw together the split ends of the strap. The member 79 extends radially beyond casing 73 (Fig. 11), terminating with a handle 85, by which the sleeve 77 and with it the magneto parts carried by frame 52, may be shifted about the axis of shaft *s* to effect variations in timing.

The breaker point operating cam 38 may be fixed to the inductor as indicated in Fig. 12 or it may be movably mounted thereon as shown in Fig. 1. In Fig. 1 the cam 38 is integrally connected to an annular ring 86, which encompasses the bearing sleeve 61 of the inductor 25 and lies flat against the outer end face thereof. Ring 86 is pivoted to the inductor at 87 and carries a weight 88. A spring 89, interposed between sleeve 61 and a spring seat 90 acts to press the cam 38 radially outwardly. Such movement is limited by the abutment of the lower part of ring 86 with the lower part of the sleeve. The weight 88, after the inductor exceeds a certain predetermined speed, tends to move radially outwardly by centrifugal force and thereby draw cam 38 inwardly against the action of spring 89 sufficiently to prevent it from moving the breaker point lever,—thus governing the engine by cutting out the ignition. The tension of spring 89 is preferably adjustable. Its seat 90 (Fig. 10) is threaded on a stud 91 fixed to cam 38. A flat spring 92 secured at one end to ring 86 bears against the serrated upper end 93 of seat 90 to hold it in its various positions of adjustment.

In Figs. 1 and 2, I have indicated how the rotary part of the magneto may be lubricated. A wick 94, leading from the engine crankcase or any suitable oil reservoir extends through the bottom of casing 71 into the same, passing between plate 56 and flange 66 and through stud 60. An axially directed slot is cut in stud 60 and the wick

is bent to lie in this slot and engage the inductor sleeve 61.

The operation of the magneto should be clear from the foregoing description and need only be briefly summarized. The inductor 25, driven as indicated or in any other suitable way from the engine, rotates continuously in the direction of the arrow shown in Fig. 1. This inductor, for the 10 larger part of each revolution, cooperates with the cores 22 to maintain a substantially closed magnetic circuit from the magnetic source 20 through the primary and secondary coils on cores 22. Periodically, this 15 normally closed magnetic circuit is suddenly broken at two points by the two notches 26 in the inductor coming simultaneously into register with the two cores. At or about this time, the breaker points 27 and 28 are 20 separated by cam 38 and the primary circuit is thereby broken. This results in a sudden decrease of flux in cores 22 and the generation of an E. M. F. in the secondary windings. After this E. M. F. has been 25 produced, the primary circuit is maintained open for a short interval until the unnotched part of the inductor again comes into very close proximity to the cores, permitting the rapid building up of flux in the magnetic 30 circuit under the most favorable conditions.

The advantages of the invention can be best appreciated and visualized from an inspection of Figs. 3 and 4 and a comparison of them with the drawings of the above mentioned patent. The flywheel *f* is of the same type and of the same size. A large part of its area is utilized for the reception of fan blades *b*, leaving only a very small inner cylindrical space available for the magneto. 40 The Hendrickson magneto is altogether too large to fit into the aforesaid small available space. The magneto of this invention, however, has been made to fit into such space and this has been done without shortening 45 the desirable long magnets of the Hendrickson magneto and without sacrifice in effectiveness of the magneto. The magneto is highly efficient and adequately meets the demands of the trade, yet its parts have been 50 compacted into much smaller compass than has been possible heretofore, so far as I am aware. Another graphic illustration of the compact arrangement of magneto parts is found in Fig. 11, which shows the same 55 magneto housed within the very small flywheel of a portable outboard motor, such as are widely used on rowboats and the like. Actually, the magneto will fit within 60 a circular space somewhat less than seven inches in diameter. This striking result has been effected by a most efficient utilization of a minimum amount of material, compatible with effectiveness of operation, and by a positioning of the parts around the 65 periphery of the inductor into a new and

exceedingly effective arrangement. The advantages stressed in the Hendrickson patent are realized in this magneto and the small, compact and relatively light weight magneto has been obtained without a corresponding 7 reduction in efficiency.

The invention has been disclosed herein, in an embodiment at present preferred, with detailed variations, for illustrative purposes but I desire to claim my invention in the 7 broadest possible legal manner.

What I claim is:

1. A magneto, comprising, an unwound rotary inductor in the form of a cylindrical member of magnetic material except for substantially diametrically opposed non-magnetic portions in its outer periphery, a pair of cores of magnetic material mounted in substantially diametrically opposed relation one on each side of the inductor with the inner end of each disposed in closely adjacent relation to said periphery, a permanent magnet substantially paralleling the cores and disposed nearly tangential at its neutral point to said periphery, members of magnetic material one for each core for connecting the outer end of each core to the adjacent polar extremity of said magnet, said magnet and members lying entirely within a circle struck from the axis of said inductor as a center and with a radius equal to the radial distance measured along the axis of a core from the axis of the inductor to the outer face of the member connected to such core, and coils on said cores, said cores constituting the sole means for conducting the flux from said magnet to the inductor. 9

2. A magneto, comprising, an unwound rotary inductor in the form of a cylindrical member of magnetic material except for substantially diametrically opposed non-magnetic portions in its outer periphery, a pair of cores of magnetic material mounted in substantially diametrically opposed relation one on each side of the inductor with the inner end of each disposed in closely adjacent relation to said periphery, each of said non-magnetic portions having a peripheral extent not greatly in excess of the width of a core, a permanent magnet substantially paralleling the cores and disposed nearly tangential at its neutral point to said periphery, members of magnetic material one for each core for connecting the outer end of each core to the adjacent polar extremity of said magnet, said magnet and members lying entirely within a circle struck from the axis of said inductor as a center and with a radius equal to the radial distance measured along the axis of a core from the axis of the inductor to the outer face of the member connected to such core, and coils on said cores, said cores constituting the sole means for conducting the flux from said magnet to the inductor. 11

3. A magneto, comprising, an unwound rotary inductor in the form of a cylindrical member of magnetic material except for substantially diametrically opposed non-magnetic portions in its outer periphery, a pair of cores of magnetic material mounted in substantially diametrically opposed relation one on each side of the inductor with the inner end of each disposed in closely adjacent relation to said periphery, each of said non-magnetic portions having a peripheral extent not greatly in excess of the width of a core, a permanent magnet substantially paralleling the cores and disposed nearly tangential at its neutral point to said periphery, members of magnetic material one for each core for connecting the outer end of each core to the adjacent polar extremity of said magnet, said magnet and members lying entirely within a circle struck from the axis of said inductor as a center and with a radius equal to the radial distance measured along the axis of a core from the axis of the inductor to the outer face of the member connected to such core, said cores constituting the sole means for conducting the flux from said magnet to the inductor, primary and secondary windings on said cores, a closed electrical circuit including said primary winding and breaker point mechanism for opening and closing said circuit and maintaining said circuit normally closed and opening said circuit when said non-magnetic portions break the magnetic circuit through said cores.

4. A magneto, comprising, an unwound rotary inductor in the form of a cylindrical member of magnetic material except for substantially diametrically opposed non-magnetic portions in its outer periphery, a pair of cores of magnetic material mounted in substantially diametrically opposed relation one on each side of the inductor with the inner end of each disposed in closely adjacent relation to said periphery, a permanent magnet substantially paralleling the cores and disposed nearly tangential at its neutral point to said periphery, members of magnetic material one for each core for connecting the outer end of each core to the adjacent polar extremity of said magnet, and coils on said cores of a diameter greater than their length and substantially filling the space between their cores and the adjacent parts of said magnet.

5. A magneto, comprising, an unwound rotary inductor, relatively stationary field elements comprising, a magnet, a pair of cores and extensions one from each core for connecting them one to each polar extremity of the magnet, said cores disposed on opposite sides of the inductor with their inner ends in close proximity thereto and extending radially away from the inductor with

their outer ends connected one to each extension at one end thereof, said magnet extending in closely adjacent relation and nearly tangential at its neutral point to the periphery of the inductor, the outer faces of said extensions substantially converging in a direction from the core ends and toward the magnet ends, said cores constituting the only flux conducting means cooperating with the inductor, and generating windings on said cores.

6. A magneto, comprising, an unwound rotary inductor, relatively stationary field elements comprising, a magnet, a pair of cores and extensions one from each core for connecting them one to each polar extremity of the magnet, said cores disposed on opposite sides of the inductor with their inner ends in close proximity thereto and extending radially away from the inductor with their outer ends connected one to each extension at one end thereof, said magnet extending in closely adjacent relation and nearly tangential at its neutral point to the periphery of the inductor, said cores constituting the only flux conducting means cooperating with the inductor, and generating windings on said cores, all the aforesaid elements lying within a circle struck from the axis of the inductor as a center and with a radius equal to the radial distance measured along the axis of a core from the axis of the inductor to the outer face of such core's extension.

7. A flywheel magneto, comprising, a relatively stationary but angularly adjustable and substantially cylindrical casing closed at one end and the opposite end of which is adapted to be substantially closed by the flywheel, a rotary inductor disposed centrally within said casing and mounted substantially in axial alignment with the flywheel to turn therewith; and field elements mounted stationarily in the casing and comprising a magnet, a pair of cores, and extensions one for each core for connecting them one to each polar extremity of the magnet, said cores mounted on opposite sides of the inductor with their inner ends in close proximity thereto and extending radially away from the inductor with their outer ends connected one to each extension at one end thereof, said extensions extending along the inner wall of said casing in the same general direction to said magnet, said magnet extending in closely adjacent relation and nearly tangential at its neutral point to the periphery of the inductor, said cores constituting the only flux conducting means cooperating with the inductor; and generating windings on said cores.

8. A magneto, comprising, a pair of cores mounted in axial alignment with their inner ends in axially spaced relation, an unwound inductor rotatable between said inner ends

- and in closely adjacent relation therewith, said inductor having in its periphery diametrically opposed non-magnetic portions, each of a peripheral extent not greatly in excess of the width of a core, the inductor except for such portions being cylindrical, a permanent magnet extending parallel to the cores and closely adjacent and nearly tangential at its neutral point to the periphery of the inductor, an extension on each core for connecting it to the adjacent polar extremity of said magnet, primary and secondary coils on each core, a closed electrical circuit including the primary coils, and breaker point mechanism for normally maintaining said circuit closed and for opening it when said non-magnetic portions align with the cores and produce a double break in the magnetic circuit from said magnet, all the aforesaid elements lying within a circle, the center of which is the axis of the inductor and the radius of which is the distance measured along the axis of a core from the axis of the inductor to the outer face of the extension connected to said core.
9. A flywheel magneto, comprising, a relatively stationary circular and substantially cup shaped casing to cooperate with a flywheel and provide a substantially cylindrical enclosure, an unwound inductor disposed centrally within said casing and mounted in axial alignment with the flywheel to rotate therewith, said inductor being a cylindrical member of magnetic material except for substantially diametrically opposed non-magnetic portions in its periphery, a pair of cores mounted in substantially diametrically opposed relation with the inner ends of each in closely adjacent relation to the periphery of the inductor and extending in opposite directions from the inductor to the inner wall of said casing, an extension from the outer end of each core extending along said wall, a permanent magnet substantially paralleling the cores and interconnecting said extensions and lying closely adjacent and nearly tangential at its neutral point to the periphery of the inductor, primary and secondary windings on said cores, a closed electrical circuit including the primary winding, and breaker point mechanism for controlling said circuit.
10. A magneto, comprising, a rotary inductor, a pair of cores mounted one on each side of the inductor in substantially diametrically opposed relation with their inner ends in close proximity to the periphery of the inductor, each core being of a length no greater than the radius of the inductor, a coil element on each core of a diameter substantially twice its axial length, an extension from the outer end of each core, the inner face of each extension extending from its core in parallel relation with the outer end face of the coil element on such core to the periphery of the element and then turning and extending in a direction parallel to the axis of said element and in closely adjacent relation to the periphery thereof and terminating with a magnet receiving end, and a permanent magnet extending substantially parallel with the axes of the cores and interconnecting said ends of the core extensions and disposed closely adjacent and nearly tangential at its neutral point to the periphery of the inductor, said magnet and extensions lying entirely within a circle struck from the axis of the inductor as a center and with a radius equal to the distance taken along the axis of a core from the axis of the inductor to the outer face of the extension.
11. A magneto, comprising, a rotary inductor, a pair of cores mounted one on each side of the inductor in substantially diametrically opposed relation with their inner ends in close proximity to the periphery of the inductor, each core being of a length no greater than the radius of the inductor, a coil element on each core of a diameter substantially twice its axial length, an extension from the outer end of each core, the inner face of each extension extending from its core in parallel relation with the outer end face of the coil element on such core to the periphery of the element and then turning in a direction parallel to the axis of said element and in closely adjacent relation to the periphery thereof and terminating with a magnet receiving end, and a permanent magnet extending substantially parallel with the axes of the cores and interconnecting said ends of the core extensions and disposed closely adjacent and nearly tangential at its neutral point to the periphery of the inductor, said inductor, cores and extensions forming a magnetic circuit from said magnet of which the inductor is the movable element and said cores constituting the only part of said circuit which cooperates with the inductor, said magnet and extensions lying entirely within a circle struck from the axis of the inductor as a center and with a radius equal to the distance measured along the axis of a core from the axis of the inductor to the outer face of the extension.
12. A flywheel magneto, comprising, a support, a cup-like casing having an end wall secured to said support and an outwardly projecting peripheral flange, an annular bearing fixed to and projecting from said support within said flange, a rotary inductor rotatably mounted on said bearing and comprising a laminated member of hollow cylindrical form except for substantially diametrically opposed non-magnetic portions in its periphery, means for rotating the inductor, stationary field elements mounted on said support and including a magnet, a pair of cores and extensions there-

of for connecting each to a polar extremity of the magnet, said cores mounted on opposite sides of the inductor and extending radially therefrom toward the peripheral wall 5 of said casing, said extensions extending along said wall from the cores to the ends of the magnet, primary and secondary windings on said cores, a closed electrical circuit including the primary winding, and 10 breaker point mechanism for controlling said circuit.

13. A flywheel magneto, comprising, a stationary support having a hollow cylindrical stud extending from one face thereof, a drive 15 shaft passing through said stud, a driving member fixed to said shaft, relatively stationary and movable magneto elements effective on relative rotation to generate an electromotive force, the movable element being 20 mounted to turn on said stud with one end face adjacent said support and the other adjacent an end face of said member, and a drive pin fixed to said face of said member eccentrically thereof and extending substantially 25 parallel to the axis thereof to said movable element with its free end operatively engaged with the latter for turning the same.

14. A flywheel magneto, comprising, a support, a drive shaft, a member fixed to said 30 shaft, a substantially cup-shaped casing having a flat end wall and a circular flange thereon cooperating with said member to provide an enclosure, a relatively thin flat plate contiguous with the inner face of said 35 end wall and secured with the latter to said support, both plate and casing having a hole through which said shaft passes, a magnet and polar extensions each connected at one 40 end to one polar extremity of the magnet, both magnet and extensions being supported by said plate within said enclosure, a pair of cores connected one to each extension at the other end thereof and extending radially toward the center of the casing, coils on 45 said cores, and an unwound inductor fixed to the inner face of said member and rotatable between the inner ends of said cores.

In testimony whereof I have affixed my signature.
